EMERGENCY IGNITION UNIT

Angelo V. Sellar, Hatboro, Pa.

Application November 18, 1944, Serial No. 564,105

1 Claim. (Cl. 123—148)

1

The invention herein disclosed relates to ignition systems of the battery distributor type and is in the nature of an improvement on that disclosed in Patent No. 2,152,650 of April 4, 1939.

The patent referred to involved the provision of a vibrator connected so that it could be cut into the low tension or breaker side of the ignition system. The distributor would then serve, as before, to carry the high tension current to the spark plugs. For such operation, however, the regular distributor brush was usually replaced by a brush narrowed at the end to reduce the possibility of pre-ignition.

Important objects of the present invention are to utilize all the advantages of the earlier invention but to avoid any need for substitution or use of special distributor arms.

Other objects are to enable the connection of the emergency unit in place by simply disconnecting the one wire leading from the primary of the spark coil to the insulated terminal of the breaker and to furnish the unit in such a form that anyone, without any previous knowledge or experience in the matter, may quickly, easily and accurately connect the unit in an ignition system and without fear of injury to any of the parts in the system.

Additional objects are to provide an ignition unit which primarily for emergency and difficult starting uses may, if desired, be kept more or less continuously in service as a desirable addition for increasing power, reducing fuel consumption and other advantages.

Other desirable objects and the novel features by which the purposes of the invention are attained are set forth or will appear in the course of the following specification.

The drawing accompanying and forming part of the specification illustrates a present commercial embodiment of the invention but structure may be modified and changed as regards the immediate disclosure, all within the true intent and broad scope of the invention as hereinafter defined and claimed.

Fig. 1 in the drawing is a diagrammatic view illustrating the invention as applied to and used in conjunction with an ordinary battery ignition system;

Fig. 2 is a plan view of the complete unit;

Fig. 3 is a reverse plan view showing the parts inside the can or container;

Figs. 4 and 5 are broken cross sectional views as on substantially the planes of lines 4—4 of Fig. 3 and 5—5 of Fig. 2.

The wiring diagram is similar to that in the

2

above identified patent in embodying a battery 7, key operated switch 8, primary winding 9 connected by wiring 10 with the breaker 11 operated by cam 12 on the same engine driven shaft carrying the distributor arm 13, the latter connected by wire 14 with the secondary, high tension winding 15 of the spark coil and cooperating with terminals 16 connected with the several spark plugs 17. Also, there is shown a condenser 18 across the breaker points.

The emergency unit of the present invention, as in the prior patent, embodies a buzzer or electromagnetic circuit interrupter or vibrator 19 which can be cut into the primary circuit of the system and which will operate through the spark coil of the system to produce a flow of high tension current, delivery in proper sequence to the spark plugs by the rotating distributor arm.

In the present invention, however, this vibrator, 20 instead of being merely a substitute to be used in place of the breaker unit, can be used either as such a substitute or to supplement and electrically cooperate with the breaker. It is this last mentioned phase of the invention which enables the emergency unit to be used in the system with the regular or standard form of distributor brush and without causing detonation and pre-ignition when so used.

In the present illustration the unit is equipped 30 with two flexible leads 20, 21, adapted to be connected respectively with the primary terminal 22 of the spark coil and with the insulated terminal 23 of the breaker, after the normal connection indicated by the broken line 10 has been 35 removed.

To provide the desired selective or combined use of the conventional and emergency ignition systems, separate control switches 26 and 25 are connected as indicated in Figs. 1 and 3. The 40 lead 29 from the spark coil is connected with one terminal 26 of the conventional ignition switch 25 and the lead 21 to the breaker is connected with the other terminal 27 of this same switch. A short wire 28 connects the spark coil terminal 26 of switch 25 with terminal 29 of the emergency control switch 24. The other terminal 30 of this switch is connected by wire 31 with winding 32 of the vibrator. The other end of this winding is connected by wire 33 to the insulated support 34 carrying the fixed contact 35. A wire 36 extends from this contact support to one side of a condenser 37. The other side of this condenser is grounded by wire 38 shown as soldered to the "can" 39 forming the container 50 and support for the several parts of the unit.

The frame of the vibrator is shown as made up of a generally L-shaped bracket 40 secured by a screw 41 to the top of the can, thus providing the necessary ground connection for the vibrating armature 42 mounted on said frame and carrying the vibrating contact 43.

The metallic container may be mounted on the back of the dash or other conveniently accessible position, where it will be grounded on the frame of the vehicle or other mechanism.

When the conventional ignition switch 25 is closed, the regular ignition circuit will be closed through the breaker, as is clear from Fig. 1. If this switch is left open and emergency switch 24 closed, circuit will be through the lead 20 from the spark coil and the cross connection 28 to switch 24 and through that switch and connection 31 to the vibrator coil and vibrator contacts 35, 43, to ground and through connection 36 to the condenser 37 and ground. This will provide a flow of sparks at the high tension side of the system to be distributed by the brush 43. Alternate use of these two switches enables ignition to be tested at will through either the regular system or through the emergency unit. Preferably and usually, however, when there is any possibility of need for the emergency system, both these switches will be closed. This then puts the vibrator and its condenser in a parallel circuit with the breaker and its condenser. When the breaker is closed it short circuits the vibrator but when the breaker opens the vibrator starts to vibrate, producing a delayed or retarded spark at the distributor. Both condensers, the conventional one 18 at the breaker and the extra one 37 at the vibrator, then discharge providing a hotter, higher voltage retarded spark. As the breaker closes the spark will be continued or extended through the inertia effect of the vibrator. This is highly desirable for cold starting or flooded carburetors because besides being late the spark has a longer time cycle in which to effect complete ignition.

By eliminating detonation the invention enables longer operation in high gear, better hill pulling power, conservation of fuel and other advantages. The invention also enables starting under weak battery or generator conditions or with weak spark plugs or with faults in the coil, condenser, breaker arm, governor or other portions of the system.

Instead of two separate switches such as shown, a single 3-way switch may be employed and this may be used in conjunction with or in place of

the conventional key operated switch. In the latter instance the switch mechanism of this invention would be used as well for turning the ignition on and off and could be used for conventional operation by putting it in the conventional position, or for emergency operation by putting it in the emergency position, or for emergency and spark retarded operation by putting it in the position with both circuits, that is, the regular breaker circuit and the vibrator circuit closed.

Instead of being added unto the conventional system as an emergency attachment, the vibrator may be included as part of the original equipment, mounted and connected ready to be used whenever required. Also, the invention may be made up as a handy complete unit adapted to be carried about for servicing engines that may have failed to start. The use of this emergency unit, whether temporarily or continuously, does not injuriously affect the engine and, due to avoiding pre-ignition, may actually be of benefit to the engine and associated mechanism.

What is claimed is:

25 An emergency unit for maintaining a conventional battery distributor ignition system in operation under conditions where it might not ordinarily operate because of weak battery or faults in the breaker mechanism or the like and comprising a magnetic circuit interrupter and means for connecting the same with the primary winding of the conventional spark coil of the system in parallel with the conventional coil and breaker circuit of that system and whereby said 30 magnetic interrupter operating through the battery, coil and breaker connections of the conventional system will provide a continuous succession of interruptions in the primary circuit in parallel with the breaker circuit and thereby enable 35 the distributor of the system to function in the conventional manner, said connecting means including two independently operable switches 40 separate and apart from the conventional ignition switch of the system and arranged, one switch to cut the breaker mechanism into and out of service and the other switch to cut the magnetic circuit interrupter into and out of service and whereby either or both said breaker mechanism and said magnetic circuit interrupter 45 may be in service at one and the same time and said magnetic circuit interrupter be used either above or in parallel with the conventional coil and breaker circuit.
